(57) **CLAIM**

We claim the ornamental design for a cap, as shown and described.

DESCRIPTION

FIG. 1 is a front perspective view of a cap, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof; and,

FIG. 7 is a top plan view thereof.

In the drawings, the broken lines immediately adjacent the shaded areas represent the bounds of the claimed design, while all other broken lines are directed to environment; the broken lines form no part of the claimed design.
